UNITED STATES PATENT OFFICE.

ERVIN LEVI BATES, OF OAKDALE, NEBRASKA.

GATE-OPENER.

1,247,921.

Specification of Letters Patent. Patented Nov. 27, 1917.

Application filed April 14, 1917. Serial No. 161,992.

To all whom it may concern:

Be it known that I, ERVIN LEVI BATES, a citizen of the United States, residing at Oakdale, in the county of Antelope, State of Nebraska, have invented a new and useful Gate-Opener; and I do hereby declare the following to be a full, clear, and exact description of the invention, such as will enable others skilled in the art to which it appertains to make and use the same.

The present invention relates to a gate opening mechanism, and has for its object to provide a device of this character which embodies novel features of construction whereby a gate can be opened by the occupant of an approaching vehicle and subsequently closed after passing through the gate opening without the necessity of dismounting from the vehicle.

Further objects of the invention are to provide a gate opening mechanism which is comparatively simple and inexpensive in its construction, which can be easily manipulated, and which is dependable in its action and not liable to get out of repair.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a side elevation of a gate opening mechanism constructed in accordance with the invention.

Fig. 2 is a transverse sectional view through the same on the line 2—2 of Fig. 1.

Fig. 3 is a detail sectional view of one of the bearing supporting sleeves.

Corresponding and like parts are referred to in the following description and indicated in all the views of the drawings by the same reference characters.

Referring to the drawings, which illustrate a preferred embodiment of the invention, the reference numerals 1 designate a pair of spaced standards which are arranged upon one side of the roadway and have the upper ends thereof bifurcated to provide for the pivotal mounting of the operating levers 2. The gate itself may be of any suitable construction, although in the present instance it is shown as formed with upright

end bars 3 connected at their middle points by a horizontal rail 4, the extremities of the end bars being connected by horizontal rods 5 and diagonal braces 6. If desired, woven wire netting may be stretched upon the gate.

The end bar 3 at the pivot end of the gate is rigidly secured to the middle portion of a horizontal bar 7 which is arranged at right angles to the plane of the gate and journaled between the two standards 1 so as to

turn about a horizontal axis. In the present instance the extremities of the horizontal bar 7 are shown as terminating in trunnions 7^a which are journaled within suitable bearings 8 upon sleeves 9 which are fitted upon the respective standards 1 and firmly secured thereto at the proper elevation. These sleeves 9 may be conveniently formed of sheet metal, and are provided at their lower ends with integral laterally projecting sleeves 10 which receive and position the extremities of a horizontal strut member 11 which is arranged between the standards 1 and below the pivot bar 7. This horizontal strut 11 may be secured to the positioning sleeves 10 and standards 1, and serves to hold the standards 1 properly spaced from each other. A horizontal tie rod 12 is arranged under the strut 11 and connects the standards 1, extending through the latter and having the ends thereof threaded to receive nuts 13 which bear against large washer members 14. It will thus be obvious that the strut 11 and tie rod 12 coöperate with each other to hold the standards 1 at exactly the proper distance apart, since the strut prevents the standards from coming together, while the tie rod prevents the standards from spreading apart.

Horizontally disposed diagonal braces 15 extend between the pivot bar 7 and the central rail 4 of the gate in order to hold the gate rigidly in proper position and prevent lateral swinging thereof. Secured to this horizontal rail 4 of the gate at a point suitably spaced from the pivot bar 7 are the laterally projecting arms 16 which terminate in balls 16^a upon which socket members 16^b are loosely fitted. The socket members 16^b are connected by coil springs 21 to cables 17 which extend downwardly from the inner ends of the operating levers 2. The outer and longer ends of the operating levers 2 extend in opposite directions along the side of the road and have suitable cables or handles 18 applied thereto. A person approach-

ing the gate from either direction will pull downwardly upon the handle 18 of the corresponding operating lever 2 and thereby cause the gate to be swung over on the opposite side of the standards 1. The resiliency of the springs 21 will admit of the gate being easily swung beyond a dead center when it will drop down on the ground on the other side of the standards 1. After passing through the gate opening the gate can be closed by pulling upon the handle 18 of the other operating lever 2, and both the opening and closing operations can be performed without dismounting from a vehicle. When the gate is closed the swinging end thereof is received between the spaced sides 20 of a divided post, the upper ends of the spaced sides being flared, as indicated at 20^a for the purpose of directing the gate into the space between the sides when the gate is permitted to swing downwardly into a closed position.

Having thus described the invention, what I claim as new and desire to secure by Letters Patent, is:—

1. A device of the character described, including a pair of spaced standards, sleeves slidably mounted upon the respective standards and provided with corresponding bearings, means for securing the sleeves in an adjusted position, a horizontal strut extending between the standards, positioning sleeves carried by and projecting laterally

from the before mentioned sleeves, said positioning sleeves receiving the ends of the horizontal strut, a horizontal bar extending between the standards and having its ends journaled within the bearings of the sleeves, a gate having one end thereof rigid with the horizontal bar and mounted to swing upwardly in a vertical plane with the axis of the horizontal bar as a center, operating levers pivotally mounted upon the upper portions of the standards, and cable connections between the operating levers and the gate. 45

2. A device of the character described, including a pair of spaced standards, a gate pivotally mounted between the standards to swing upwardly in a vertical plane about a horizontal axis, operating levers pivotally mounted upon the upper ends of the standards, arms projecting laterally from the sides of the gate and terminating in balls, sockets loosely applied to the balls, and cable connections between the sockets and the operating levers. 50

In testimony whereof I have signed my name to this specification in the presence of two subscribing witnesses.

ERVIN LEVI BATES.
